UNITED STATES PATENT OFFICE

ROBERT E. WALLISER, OF CHICAGO, ILLINOIS

FRINGE-TASSELING MACHINE

Application filed March 28, 1929. Serial No. 350,547.

This invention relates to a fringe tasseling machine of the general type disclosed in my Patent No. 1,663,534, granted March 20, 1928, being employed for making tassels used on 5 fringe heading material, trimmings, borders, curtains, etc., etc.

The object of the invention is to provide certain improvements in a machine of the kind described that will provide a means of 10 making tassels for fringe heading material and securing same thereto in groups of greater or less numbers, and these groups in different positions, thus affording a fringe heading with tassels arranged thereon in a 15 manner to provide a variety of adorning effects.

Another object is to provide a fringe tasseling machine with improved means for applying binding material to tassels.

20 A further object is to provide improved mechanism in a machine of the kind described that will securely and expeditiously bind groups of tassels at variable spaces apart, thus producing diversified effects in a fringe heading ornamented with tassels.

Other objects and advantages of the present 25 method of fabrication and the means employed therefor will appear more fully in the details hereinafter set forth when taken in connection with the accompanying drawings, in which:

Fig. 1 is a top plan view of a machine embodying my invention, illustrating the left and right-hand power units of the dies, and the cooperating feeding mechanism;

Fig. 2 is an end elevational view taken on line 2—2 of Fig. 1 of the right-hand side of the machine, illustrating details of the feeding mechanism;

Fig. 3 is an enlarged detail view illustrating the formation of one of the groups of tassels;

Fig. 4 is a transverse section, taken on line 4—4 of Fig. 1, illustrating the means for guiding the binding wire from a supply source (not shown); also showing in face elevation the male dies and the combing mechanism for the fringe heading;

Fig. 5 is an elevational view taken on line 5—5 of Fig. 1, at the rear of the machine, looking in the direction of the arrows, illustrating

the male and female power units; the fringe heading being shown in the normal position assumed when fed through the mechanism;

Fig. 6 is a plan sectional view of the male and female dies and the cams which control 55 the slideable die bars, the heading and fringe being shown in normal position;

Fig. 7 is a longitudinal sectional view, certain parts being shown in elevation, of the male die and parts associated therewith for 60 the operation of the slideable male die bars;

Fig. 8 is a plan view taken on line 8—8 of Fig. 7, parts being shown in section;

Fig. 9 is a transverse sectional view taken 65 on line 9—9 of Fig. 7, illustrating the upper and lower adjustable male die blocks in section;

Fig. 10 is a plan view, partly in section, illustrating the coacting male and female die bars in the position assumed in an intermediate stage of the process of forming an upper 70 tassel for the fringe heading;

Fig. 11 is a longitudinal sectional view, with parts shown in elevation, of the female die bar and associated power units for the 75 operation thereof;

Fig. 12 is a plan view, similar to Fig. 6, taken on line 12—12 of Fig. 11, parts being shown in section;

Fig. 13 is a cross sectional view taken on 80 line 13—13 of Fig. 11;

Fig. 14 is a plan detail view of one set of the reciprocating male and female dies, illustrating the closed position of the die members with the fringe cords tied;

Fig. 15 is a detail end view of one of the female die bars illustrating the grooves which guide and receive the binding wire;

Fig. 16 is a front elevational view of the housing for the male die bar and associated power unit, the table being shown in section, illustrating the mechanism for feeding the binding wire;

Fig. 17 is a detail view, taken on line 17—17 of Fig. 16, illustrating the cushion spring arrangement employed in the feeding mechanism;

Fig. 18 is a plan view taken on line 18—18 of Fig. 16, of the lower jaw for gripping the binding wire to be fed;

Fig. 19 is an elevational view of the guide pins and compression springs which are operatively engaged with the plate which is frictionally engaged with the wire used in binding the tassels;

Fig. 20 is a rear detail view of the combing or brushing mechanism employed in straightening the fringe cords;

Fig. 21 is an elevational front view of the heading and fringes showing completed tassels as manufactured and grouped by the mechanism embodied in my invention.

Referring to the drawings in which similar characters of references indicate corresponding parts in the several views of the preferred form of my invention, 25, 26 designates supporting members of a frame having ribs 27, 28 mounted on flat bars 29 and 30 and secured thereto by screws 31, the frame being supported on and secured to end standards 32 by the screws 33. The members 25, 26 are provided with front walls 34, 35 and rear walls 36, 37, the walls 34, 36 being provided with a cap 38 which is secured thereto by screws 39, while the walls 35, 37 are also provided with a cap 40 secured thereto by screws 41, this construction forming the housings for the male and female dies. The caps 38 and 40 have projecting bearing arms, one of these arms 41' being for the female die shaft while the arm 42 serves as the corresponding member for the male die shaft.

Mounted below the frame members 25, 26 are the right and left-hand brackets 43, 44; bracket 43 being secured to the female die housing and bracket 44 and to the male die housing by means of the bolts 45. The bracket 43 has a bearing arm 46 opposed to the upper bearing arm 41' in which a shaft 47 is rotatably mounted and held therein against longitudinal displacements by collars 48. Bracket 44 of the male die housing also has a bearing arm 49 extending laterally therefrom in opposed relation to the upper bearing arm 42, and mounted in these bearing arms 49 and 42 is the male die shaft 50 which, in a manner similar to that described with reference to the female die shaft 47, is secured against displacement in the bearing arms 49, 42 by the collars 51. The brackets 43, 44 are further provided with downwardly projecting arms 52 and 53 in which a main driving shaft 55, passing through the cross bar 54 fixed to an end standard, is secured and held in place by the collars 56.

On the shaft 55 a pulley wheel 57 is secured, which is engaged by a belt 58 connected to a source of power (not shown). Bevel gears 59 and 60 fixed to the driving shaft 55 are engaged with coacting bevel gears 61 and 62 on the female and male die shafts 47 and 50. Mounted upon the front rib 27 is a pair of bearing brackets 63, secured by cap screws 63', these brackets supporting a

feeding shaft 64 provided with collars 65 and having thereon a feeding roller 66. This feeding roller 66 has its peripheral face roughened or covered with a suitable material to frictionally engage the fringe heading 90 and draw the latter through the tassel forming mechanism of the machine. A ratchet wheel 67 is arranged on the outer end of the shaft 64 and fixedly secured thereto by the axially disposed cap screw 68. A swinging arm 69, mounted loosely on the shaft 64, has a stud screw 70 to which is pivoted an adjustable link 71 threaded in a socket at the end of a yoke arm 72 having a slot 73 in which the main driving shaft 55 rides, the latter being confined therein by a collar 74.

At the inner side of the yoke arm 72 a stud screw 75 having a roller 76 is secured, the roller engaging a cam 77 fixed to the main driving shaft 55. A feeding dog 79 pivoted on a stud 78 on the side of the swinging arm 69 is held to the ratchet wheel 67 by a spring 80. The ratchet wheel 67 is also provided with a locking dog 81, pivoted on stud bolt 82 to a bracket 83 which is held by the bolt 84 to the rib member 27, a spring 85 being used to hold the locking dog 81 to the ratchet wheel 67.

An adjustable stop member 86 is threaded in a hole in a bracket 87 fastened to the frame or table member 27, said stop member 86 being adjustably secured in the position desired by a lock nut on the shank thereof and engaging the bracket 87. It will here be noted that the arm 69 draws the feeding dog 79 in engagement with ratchet wheel 67 whereby to rotate the latter as the cam 77 moves the yoke 72 and link 71 connected to the arm 69 a predetermined length, and that the spring 88 fastened to the bracket 87 and to the yoke 72 will keep the roller 76 and the cam 77 in engagement and return the arm 69 into engagement with the stop member 86, the purpose of the stop member 86 being to limit the extent of movement of the swinging arm, and thereby regulate the feeding of the fringe heading 90.

A guideway 89 is provided on the rib member 28, the purpose of the guideway 89 being to prevent undue lateral movement of the fringe heading 90 having cords 91 thereon. The fringe heading passes under a guide hook 92 held between a pair of clamping nuts 93 on a screw 94 adjustably secured to the rear wall 36 of the female die housing. It also passes between the U-shaped wire guide 95, which is secured to the table member 25 by nuts 96, and the U-shaped guide 97 also secured to table member 26 by nuts 98. A guide member 99 similar to guide 95, and also having a U-shape, is secured on the adjusting screws 100 and 101 which are mounted in the front wall 35 and in the rear wall 37 of the male die housing and held in place therein by nuts 101'. The fringe heading 90

passes over the roughened feeding roller 66 and then between said roller 66 and a weighted, friction roller 102, pivoted at 103 to one end of a bell crank arm 104 rockingly mounted on a stud 105 in a bracket 106 secured to rib 27. At the outwardly projected end of the bell crank a removable weight 107 is secured.

Below the bearing arms 52, 53 and secured to the under side thereof a U-shaped bracket 108 is mounted, and cooperating with this bracket is a yoke 109 having a slot 110 therein, in which the shaft 55 is received. At the upper end of the yoke 109 a cam block 111 is secured. On the shaft 55 is fixed a hub 112 having a cam 113 integral therewith, and on the opposite side of the adjacent yoke 109 is a collar 114 in which is seated one end of a coil spring 115 that serves to yieldingly hold the yoke 109 against said hub 112 of the cam 113. A stud 116 with a roller 117 that rides upon the cam 113 is mounted on one side of the yoke 109. A downwardly projecting portion 118 at the lower end of yoke 109 has a rod 119 secured thereto, said rod passing through a slot 120 in the U-shaped bracket 108.

A coil spring 123, sleeved on the rod 119, and interposed between washers 121 and 122, provides a quick return action of the cam 113 and associated parts, after the cam has accomplished the combing or brushing process hereinafter to be described. It will be noted that by reason of the rectilinear portion 118' of the cam 113, the yoke 109 will be restored or snapped back in position to again present the combing and brushing element to another portion of the depending fringes, as described below. A cam 124 that rides upon the cam block 111 of the yoke 109 is fixed to the cam 113 so as to rotate therewith on the shaft 55. Extending upwardly from the yoke 109 is a combing arm 125 having a brush 126 thereon, which latter engages the fringe cords 91. In opposed working relation to the brush 126 an abutment plate 127 is mounted on an arm 128 having a slot 129 permitting adjustment thereof, said arm being secured to the bearing arm 46 by a bolt and nut 130. It may here be noted, that as the fringe heading 90 is conveyed through the space lying between the guide hook 92, the U-shaped members 95, 97, 99, and the abutment plate 127, the brush 126 engages the lower portions of the cords 91 that subsequently are formed into the tassels, and also the preceding tassel last formed, and straighten them out, the direct moving engagement of the brush with the cords being essentially a restrained or rather slow movement, while the return or releasing movement, on the contrary, is a comparatively quick or snap-back action.

The above described brushing or combing operation on the cords 91 of the fringe heading 90 occurs each time said heading comes

to rest in its intermittent or step-by-step movement through the machine and just preceding the process of gathering the cords and the binding thereof in the formation of the respective tassels to be presently described. This is done to secure uniformity and neatness in the resultant tasseled fringe product.

Affixed to the male die shaft 50 just above the collar 51 of the bearing arm 49 is a cam 131 that operates a rocking arm 132 pivoted on the stud bolt 133 located on a bracket arm 134, which is secured to the table 26, the rocking arm 132 being held against the cam 131 by means of the coil spring 135, the other end of the rocking arm 132 having an upwardly and inwardly directed arm 136 that lies between two feeding ratchet shoes 137 and 138 which are pivotally connected thereto by a pin 139. The two feeding ratchet shoes are pivoted on a pin 140 in the block 140' mounted on the outer end portion of the lever arm 141 pivoted also on the stud 133. The shoes 137, 138 enter the block through slots 142 and 143. Mounted in the rear portions of the slots 142 and 143 and in opposed relation to said feeding ratchet shoes 137, 138, are two cooperating members 144 and 145 which are fixedly secured to the back walls of said slots. The feeding ratchet shoes 137 and 138 are provided with circular slots 146 and 147, each of these slots having a pin 148 which serves to limit the angular movement of the said shoe, and also to unlock the gripping action of the jaws on the return movement of the operating levers 132, 136, 137, 138 and 141. The arm 141 is frictionally held by means of the plunger 149 against the arm 141 by a spring 150 retained in an adjustable hollow screw 151 provided with a lock nut 152 engaging the member 141. It will be noted, as best shown in Fig. 17, that the spring 150 impels the plunger 149 against the surface 26, and in this manner serving to maintain in yieldable binding relation the parts associated therewith.

A screw 153 for the adjustment of the ratchet shoes 137 and 138 is mounted on a bracket 154, the latter being fixed to the front rib 27. The adjusting screw is locked to the bracket by means of a nut 155, this nut providing an adjustment for the feeding ratchet shoes. Wires 156 and 157 are drawn off friction rollers (not shown) and under the guide shoes 158 and 159 which latter are fixed to a bracket 160. The wires 156 and 157, it will be noted, are maintained in spaced relation by a pair of pins 158' and 159' mounted in a post 160' secured to rib 27, the two wires 156 and 157 being held in frictional engagement against the post 160' by a plate or shoe 161, the latter plate being held in position by two pins 162 and 163. Springs 164 are interposed between the plate and nuts 164' thereby providing tension against the wires 156 and 157. It may here be noted that the feeding of the

wire from the source or supply (not shown) is accomplished by the intermittent or step-by-step action of the gripping and feeding ratchet shoes 137 and 138, which, when moved 5 by cam 131, coacting with the rocking arm 132 on which the ratchet shoes are carried, will engage the wire, moving in the direction of the arrow shown in Fig. 1.

At the lower part of the male die housing, 10 the lower male die block 166 is mounted directly on fixed rails 167, the adjusting screw 168 on the front wall 35 and the adjusting screw 169 on the rear wall 37 providing means for positioning the upper male die block 165 15 relatively to the lower male die block, on which latter it is slidably mounted. Lock nuts 170 are provided to secure the adjusting screws 168 and 169 in the position desired. A slot 171 is formed in the block 165, this slot 20 lying in a plane parallel to the adjusting screws 168 and 169. In the slot 171 a block 171' rides, said block 171' being secured by screws 172 to the lower male die block 166. Pairs of adjusting screws 173 on the front 25 wall 35 and an additional pair of screws 174 on the rear wall 37 are likewise fixed in adjusted position by lock nuts 174', these last mentioned pairs of adjusting screws serving for the adjustment of the lower male die 30 block. When the upper and lower male die blocks are placed in the position desired, they may be fixedly secured by the locking or set screws 175 which clamp the two blocks upon the rails 167. The upper male die block 165 35 and the lower male die block 166 are formed with longitudinal slots 176 and 177 in which the elements hereinafter to be described reciprocate.

As shown more clearly in Figs. 4, 6, 7 and 40 8, mounted on the left side and near the end of the upper die block 165, a tube 178 is positioned at a point where the upper binding wire 156 enters, for a purpose hereinafter described. From this wire 156 is formed the 45 loop for binding the upper part of a tassel. Mounted in the lower male die block 166, and near the upper end of the slot 177, a tube 179 is located where the lower binding wire 157 enters, the functions of this tube to be described hereinafter. Both the tubes 178, 179 and the upper and lower die blocks 165 and 166 are lockingly secured to set-screws 180, as best shown in Fig. 8.

In Figs. 6, 11, 12 and 13 it will be noted that 50 the female die housing is similar to the male die housing, the female die housing also having an upper die block 181 and a lower die block 182 similar to the blocks 165 and 166, resting upon supporting rails 183 on the table 55 25. The lower female die block 182 is adjustable by means of set screws 184 in the front wall 34 and set screws 185 on the rear wall 36, each of the said set-screws being provided with lock nuts 185', which secure the

lower female die block in position, when desired. The upper female die block is provided with a slot 186 that fits over a stationary rib or bar 187 or held in position on the lower block 182 by means of screws 188, thereby locking the upper and lower die blocks against displacement lengthwise, but permitting relative transverse movement thereof. It will also be noted that the upper female die block 181 is adjustable relatively to the lower female die block by means of adjusting screws 189 mounted on the front wall 34 and adjusting screw 94 and 190 mounted in the rear wall 36, each of said adjusting screws 189, 94 and 190 being provided with lock nuts 190'. 70 75 80

After the female upper and lower die blocks have been adjusted to the position desired relatively to the male upper and lower die blocks, they are locked by means of two set screws 191 which are similar to set screws 175 of the male die housing. The upper and lower female die blocks are provided with slots 192, 193 that extend the full length of both of the blocks, these slots being clearly shown in Figs. 6 and 11. It will now be seen that the slots 176 and 177 of the upper and lower male die blocks align with the corresponding slots 192 and 193 of the female upper and lower die blocks as shown in Fig. 6. 90

Slidably mounted in the slot 176 in the die block 165 is a reciprocating cutting and looping bar 194, having at its outer end a groove 195 which receives and retains a piece 196 that has been cut from the binding wire 156, the amount cut off being of predetermined length but of a length sufficient for binding the tassel as hereinafter described. The reciprocating slidable cutting and looping bar 194 is operated by the cam 197, which latter is adjustable on shaft 50 by means of the slot 198 provided in the face of cam 200, and a bolt 199 fixed in cam 197, said cam 200 being secured by a set screw 201 directly to the male die shaft 50 (see Figs. 5, 6 and 7). 95 100 105

The cam 200 operates a second reciprocating bar 202 which, at its forward end, has an inclined surface 202' provided for a purpose which will appear hereinafter. The reciprocating bar 202 has a downwardly and forwardly projecting pusher and bender die arm 203 which is slidably in slot 204 in the reciprocating cutting and looping bar 194. The pusher and bender die arm 203 has a dovetail slot and rib connection with the bar 194 for the purpose of allowing said bars 194 and 203 to reciprocate freely relatively to each other by the rotation of cams 197 and 200 upon the male die shaft 50. The forward pusher and bender die arm 203 at its forward end is provided with a circular groove 206, 115 120 125 wherein the cut piece of the binding wire 196 is held while the looping and bending of same is accomplished, as will presently more fully appear. It is to be noted that as the two cams 197 and 200 are operated, these cams will 130

move the two bars 194 and 202 together and relative to each other, thereby causing the bar 194 to first sever the piece 196 from the wire 156, after which the cut piece 196 is carried forward by means of the two cooperating bars 194 and 202 until said cut piece of the wire 196 engages a stop post 207 fixed to a trigger arm 208 about which the wire is initially bent by the action of cam 200 upon the reciprocating bar 202. The inclined surface 202' on the bar 202 operates a shoe 209 which passes through a slot 210 in the upper wall of the upper die block 165, the shoe 209 being fixed to the trigger arm 208 by means 10 of a nut 211 on the screw threaded shank of said shoe 209. The trigger arm 208 is pivoted on a pin 212 mounted on a lug 213 that extends from the upper male die block 165. At the outer end of trigger arm 208 a lug 214 is 20 formed against which a spring 215, held in a recess in the block 165, is pressed, said spring yieldably holding the trigger arm 208 and the stop 207 in the position shown in Fig. 7 until said arm 208 is actuated by the inclined 25 cam shoulder 202' of the bar 202 riding in engagement with the shoe 209 and thereby withdrawing the trigger arm 208 out of the path of the cutting and looping bar 194 and also of the pusher and bender bar 202.

30 In Fig. 5 it will be observed that a U-shaped bracket 215' is mounted on the bearing arms 42 and 49, said U-shaped bracket serving as a support for a plate 216 having holes for the attaching coil springs 217 and 218. At one end, the spring 217 is connected to the plate 216 by passing it through one of the holes thereof, while at the other end the spring is hooked in a hole in an arm 219 projecting rearwardly from the reciprocating 35 pusher and bender bar 202 of the male assembly, this arrangement serving to maintain the pusher bar 202 against the cam 200. One end of the other spring 218, as mentioned above, is inserted in a hole of the plate 216, 40 while its other end is secured to an arm 221 projecting rearwardly from the reciprocating male cutting and looping bar 194, the spring 218 holding said bar 194 against the cam 197. The springs 217 and 218 also function to insure the return movement of the reciprocating bars 202 and 194.

45 It will now be seen by inspection and comparison of the male and female power units and the elements associated therewith that the two reciprocating male die bars 202 and 194 must be in alignment with the reciprocating female or receiving die bar 222, as best shown in Fig. 11. The said female reciprocating receiving die bar 222 is supported 50 on the two stationary bars 187, sliding in the lower half of the slot 192, and being operated by a cam 232 rotatable with shaft 47. Another bar 223 having reciprocating movement relatively to the bar 222 is operated 55 by a cam 235, the purpose and function of

said bar 223 being set forth hereinafter. At the outer end of the reciprocating receiving die bar 222 a pair of opposed grooves 224 are provided which have intermediate diagonally extending portions with a view to forming a slight twist and overlapping of the meeting end portion of the formed binder wire 196. The reciprocating receiving die bar 222, at its upper side, has fixed thereto a plate 226 (see Figs. 6 and 11) which, when said bar 222 is reciprocated, will cause the plate 226 also to move in the same direction in the upper part of the slot 192.

60 Mounted on plate 226 is a pair of pins 227 while at the forward end of the reciprocating bar 223 a supporting member 228 is provided in which a resilient U-shaped member 229 is pivotally mounted, said member 229 being in engagement with the pair of pins 227. The U-shaped member 229 has convolutions or humps 230, the end portions of said member 229 constituting clamping fingers 229'. At the forward end of the upper slot 192 is a block or shoe 231 fixed by screws 231' to the upper female die block 181. In accordance with the arrangement described it will be noted that the U-shaped clamping member 229 is held in position by the under side of the shoe 231 and by the upper side of the plate 226, which latter when operated, 65 will move in a straight line. The bar 222 mentioned above is operated by a cam 232 having a bolt 233, which latter is adjustable in a slot 234 of the cam 235, the said cam 235 being fixed to the female die shaft 47. The cam 235 operates the bar 223 and the cam 232 operates the bar 222, which, with their associated elements as just above described, contract or move the fingers 229' of the member 229 toward each other.

70 Mounted upon the bearing arms 41' and 46 is a U-shaped bracket 236 having a cross plate 237 secured thereto, which latter is provided with holes accommodating coil springs 238 and 239, these details being best shown in Fig. 5. The spring 238 at one end is hooked to a hole in the plate 237 and at the other end is fastened in the hole of an arm 240 projected from the bar 223. The spring 239 at one end is hooked in another hole of the cross plate 237 and its other end in a hole of arm 241 extended from the reciprocating receiving die bar 222. It will here be noted that the male and female power units and their associated parts are in a large measure symmetrical with the exception of the elements which immediately coact to produce a bend in the short sections 196 of wire cut to serve as the upper binding means for the spaced groups of tassels. As best shown in Fig. 21, 75 it will be noted that the lengths of wire preferably have been so predetermined that the ends thereof slightly overlap. If desired, the sections of wire 196 provided for binding purposes may be made longer or shorter by 80

manipulation of the adjusting screw 153 in order to feed more or less wire 156 for binding purposes into the male die block, the notches 242 (Figs. 4 and 6) serving to permit cutting off a slightly longer section of wire to be used as the binder. I have found the present length of wire, as shown, preferable since the ends overlap sufficiently to prevent the detachment of any individual cord from any of the individual groups of tassels, a substantial saving of wire being effected by the comparatively short pieces used.

The parts which have been set forth in detail in connection with the elements in the upper power unit concerning the male upper die block which coact to form the upper and first bound portions 243 of the tassels, having corresponding parts in the mechanism hereinafter to be described for the making of the second or lower portions of the tassels,—this mechanism comprising the parts associated with the lower male die block, as best shown in Fig. 7. A reciprocating cutting and looping bar 244 is slidably mounted in the upper portion of the slot 177 in the lower male die block 166 and having at its outer end a grooved portion 245 which receives and retains the portion of wire 246 that has been cut off from the continuous strand of the lower binding wire 157, the amount of wire 246 cut off, as described in connection with the lower male die block, being of variable length and for the same purpose as described in connection with the piece 196 cut from the upper binding wire 156. It will be noted, as shown in Fig. 7, that in its operation the cutting and looping bar 244 is actuated by the cam 247, the latter being adjustable on the male die shaft 50 by means of a slot 248 provided in the cam 250 and cooperating bolt 249 on the cam 247, the cam 250 being secured to the shaft 50 by a set-screw 251 (see Figs. 7 and 8).

The cam 250 actuates a reciprocating bar 252 which has at its forward end a beveled or inclined surface 253, the function of which latter is the same as that of the corresponding portion 202' of the upper pusher and bender bar 202. Reciprocating bar 252 has a downwardly and forwardly projecting pusher and bender die arm 254 which is slidably in a slot 255 formed in the reciprocating cutting and looping bar 244. The bar 244 has a dovetail slot and rib connection 256 with the bar 254 which permits said bars 244 and 254 to reciprocate relatively to each other when cams 247 and 250 rotate with the shaft 50.

The pusher and bender die arm 254 has a circular groove 257 in which the section of wire 246 is engaged and pressed against the post 258 in effecting the initially looping and bending thereof. As the function and operation of the cams 247 and 250 are similar to cams 200 and 197, which has been indi-

cated above, it will be unnecessary here to enter into a description of the corresponding and similar functions of the lower die block and the associated parts.

When the cut section of wire 246 engages the stop post 258 which is fastened to the trigger arm 259, the wire will be bent about this post 258, the same as described in connection with the upper and corresponding element 207. The inclined surface 253 coacts with the shoe 260 which passes through the slot 261 in the lower male die block 166, the shoe 260 being fastened on the trigger arm 259 by the nut 262 on the screw threaded shank of said shoe 260. As best shown in Fig. 7, the lower trigger arm 259 is pivoted on the pin 263 which is mounted in a pair of lugs 264 which latter extend from the lower male die block 166. At the outer end of arm 259 a lug 265 is provided, this lug being engaged by a spring 266 which is held in a recess of the block 166, said spring coacting with the trigger arm 259 to yieldably maintain the latter in normal position, as best shown in Fig. 7.

As best disclosed in Fig. 5, coil springs 267 and 268 are secured to the plate 216 described above, the spring 267 being connected in a hole in the arm 269 projected from the reciprocating pusher and bender bar 252. The spring 268 at its outer end is correspondingly secured to an arm 270 projected from the male cutting and looping bar 244. In the same manner described above, in connection with springs 217 and 218, the springs 267 and 268 have for their purpose the insuring of the return movement of the reciprocating bars 252 and 244.

In the lower portion of the slot 193 in the lower female die block 182 is a reciprocating receiving die bar 271 which is similar to the bar 222 of the upper female die block 181. At the outer end of said reciprocating receiving die bar 271, a pair of grooves 273 and 274 is provided, these grooves having intermediate diagonally extending portions which produce the twist and overlapping of the meeting end portions of the formed binding wire 246. The bar 271 at its upper side has a plate 275 fixed thereon whereby when said bar 271 is actuated, said plate 275 will move in the upper part of the slot 193. (See Figs. 11, 12 and 13). On the plate 275 a pair of pins 276 is secured, the purpose of which will be later explained.

Another bar 272 having reciprocatory movement relative to the bar 271, functions the same as the bar 223 which latter cooperates with the bar 222 hereinbefore mentioned. At the forward end of said reciprocating bar 272 a supporting member 277 is provided in which a resilient U-shaped member 278 is pivotally mounted, the latter being in engagement with the pins above mentioned 276, the U-shaped member 278 having

convolutions or humps 279 and end portions, said U-shape member 278 constituting clamping fingers 279' for holding the fringe cords 91 while the tassel is being bound. A block 5 or shoe 280 is secured by screws 281 to the underside of the stationary bar 187, it being here noted that the U-shaped clamping member 278 is retained in position by the shoe 280 and also by the upper side of the plate 275 which, when said bar 271 is operated, moves in a straight line. The bar 271 alluded to above, is operated by a cam 282 having a bolt 283 which is adjustable in a slot 284 of the cam 285, the latter cam being secured to 10 the female die shaft 47.

On the cross plate 237, which is secured to the bracket 236, above described, additional holes are provided which accommodate the coil springs 286 and 287, as best shown in Fig. 20 12. The spring 286 which, as above mentioned, is held at one end to the plate 237, has its other end fastened to an arm 288 projected from the bar 272. The spring 287, secured at one end to the plate 237, has its 25 other end likewise secured to an arm 289 extended from the reciprocating receiving die bar 271.

It will here be observed that the elements 20 enumerated in connection with the lower die bars, together with the elements of the upper die bars, coact to produce the tassel, of which 243 constitutes the upper body portion and 290 the divided depending bound groups of cords forming the main tassel, this 25 tassel being best shown in Fig. 21.

The function and manner of operation of the machine herein described and illustrated has been in a large measure indicated by the details set forth above. It will be observed in the operation of the device that the fringe heading material 90, together with the cords 91 which are tied to form the tassels described, is carried through a guideway 89 and between adjustable guides 95 and 97. An 40 additional guide member 99 and a stop plate 127 is also provided, by which means the fringe and tassels are prevented from undue lateral movement during the operations which result in the binding of the tassels into the groups desired. The movement of the fringe heading and tassels thereon has an 45 intermittent or step-by-step action, this being accomplished by the action of yoke member 72 which, as the power driven shaft 55 is revolved, is actuated by the engagement of cam 77 engaging roller 76, it being observed that as the shaft 55 rotates the cam 77 will communicate a thrust to the yoke, consequently 50 causing the link 71 to angle the rocking arm 69 and further causing the feeding dog 79 to engage the teeth of ratchet wheel 67. While the shaft 55 is continuously rotating it will, nevertheless, be observed that the ratchet wheel 67 will have movement communicated 55 to it only when the link 71 moves in a direc-

tion to positively engage the dog 79 with the teeth of the ratchet wheel 67 to revolve same in a clock-wise direction as viewed in Fig. 2. During the return movement of the rocking arm 69, the feeding dog 79 is inoperative, passing over the teeth of the ratchet wheel 67 in a counter-clockwise direction.

As best shown in Fig. 2, careful inspection of the adjusting member 86 will show that the length of the thrust of the return movement of the rocking arm 69 is limited by abutting the end of the adjusting member 86. It will also be observed that link 71 in addition permits a relatively greater or less sweep of the arm 69 when it is shortened, which may be done by turning same in the sockets formed at the end of the yoke 72 and the short member immediately attached to the stud screw 70. It may here be observed that as the link 71 is made longer, the angle of its movement will be lessened, the effect of which, when the adjusting screw 86 is manipulated, will be to render less abrupt any changes made by turning of the adjusting screw 86.

The action of the elements which intermittently grip the wire for the step-by-step movement of the latter, to be subjected to the cutting and loop forming operations, has been alluded to above, it being observed that the adjusting screw 153 will limit the return movement of the feeding shoes 137 and 138 which grip the binding wires, this return movement therefore being of an extent capable of graduation by adjusting the stop member 153, thus producing various lengths of 90 the cut pieces 196 and 246 of the binding wires 156 and 157, respectively.

The operation of the elements within the male and female power units has also been indicated to some degree in the hereinbefore specification. Assuming the power driven shaft 55 to be revolving, movement will be communicated to the female and male die shafts 47 and 50, respectively, through the corresponding years 60, 61, 59 and 62, respectively, and the several cams secured to the female die shaft and to the male die shaft consequently will be simultaneously actuated to control the feeding, cutting and loop forming operations above indicated. These elements coact to divide the cords affixed to the fringe heading into predetermined groups which, by the mechanism indicated, may be spaced at different distances apart, thus producing a corresponding variation in the ornamental appearance of the fringe heading and tassels thereon.

The function of the upper male and female die bars and cams is to apply the short sections of binding wire to the upper part of the tassels, the completed condition of which is best shown in Fig. 21. In Fig. 3 the first completed step in the formation of a single tassel is shown, it being observed that the upper male die block together with the co- 125

acting upper female die block, produce the upper bound portions 243 of the tassel which are shown in Fig. 21 and that the corresponding lower male and female die blocks and associated elements coact to produce the lower bound portions 290.

It may here be pointed out, that by reason of the adjustability of the stop member 86 to vary the feed of the fringe heading and also due to the provision for correspondingly adjusting the position of the upper die blocks 165, 181 and for adjusting the lower die blocks 166, 182 relative to said upper die blocks, the distance between the respective tassels may be varied. That is to say, the variation in the width or distance across at which the upper binding loops 196 are applied is controlled by the length of stroke of the feeding mechanism, and the relative transverse adjustment of upper and lower die blocks centers the lower binding loops 246 with respect to the upper bindings so as to produce a neat and symmetrical product. So, too, by varying the relative positions of the upper and lower bindings 196 and 246 and also by varying the distance of separation between the upper bindings 196 the general appearance of the openwork body between the original heading or selvage 90 and the formed tassels is materially changed.

The operation in connection with the applying of the binding wire to the tassels has been in part indicated in the description of the elements immediately coacting to produce loops. Every revolution of the power driven shaft will cause a corresponding revolution of the male and female die shafts 47 and 50, respectively, which, it will be noted, revolve in opposite directions. The continuous wires 156 and 157, which are grasped and fed step-by-step forward through the machine by means hereinbefore described, are individually engaged and primarily cut by the bars 194 and 244 into sections of predetermined lengths, these sections being received in the circular grooves 206 and 257, respectively, where they are retained until the cut sections moving forward engage the stop posts 207 and 258 which, as best shown in Fig. 7, are intermittently actuated as the trigger arms 208 and 259 on which they are mounted are raised and lowered when their corresponding pusher bars 202 and 252 engage their inclined surfaces against the registering beveled surfaces of the shoes 209 and 260.

In Fig. 10 a cut section of wire is shown in an intermediate part of the operation, during which it is thrust forward for engagement with its respective post. In this figure it will be seen that the ends of the gripping fingers are in extended position to engage the number of the cords from which the completed group of tassels is formed after the application of the binding wire thereto. In Fig. 14 the pusher and bender die arm 203

is projecting forward a section of cut wire, which in configuration is substantially similar to a conventional staple to be clamped about a group of tassels which is held in the position shown by the contracted fingers of the member 229', the contraction of these fingers occurring as the humps 230 are engaged by the pins 227. As pointed out, each revolution of the power driven shaft will suffice to complete the operation of cutting a section of wire, bending same, and applying it about a tassel in a manner to provide overlapping ends of the binding element.

It will be apparent to those skilled in the use and operation of that class of devices to which my invention appertains that various modifications and embodiments may be made without departing from the spirit or sacrificing any of the advantages of the invention as defined in the appended claims.

What I claim as new and desire to secure by Letters Patent is:

1. A machine of the kind described including means for holding and passing tassel material in a step-by-step movement through said machine; means mounted in said machine and coacting with said first mentioned means for binding into unsevered spaced groups said tassel material, by independent fastening elements and feeding mechanism for presenting fastening material to said binding means.

2. A machine of the kind described including means for holding and passing tassel material having loose strands intermittently through said machine; mechanism adapted to divide and arrange said strands into unsevered groups and means connected to the machine and coacting with said first mentioned means for applying binding material to said groups to form tassels.

3. A machine of the kind described including means for holding and passing tassel material and binding material therefor intermittently through said machine, and additional means mounted in said machine and coacting with said first mentioned means for cutting binding material into selectively different lengths and applying said cut binding material to said tassel material at predetermined positions thereby separating said tassel materials into groups of tassels variably spaced.

4. A machine of the kind described including means for holding and intermittently passing tassel material having loose strands through said machine, mechanism adapted to divide and arrange said strands into unsevered groups, additional means for holding and passing binding material through the machine and an instrumentality connected to and coacting with both of said means for cutting and applying said binding material to said groups to form tassels, the ends of said binding material being overlapped rela-

- tively to each other after application to said tassel material.
5. A machine of the kind described including means for holding and intermittently passing tassel material and binding material therefor in a step-by-step movement through said machine and variable other means for cutting and applying sections of said binding material to said tassel material, the ends 10 of said binding material being maintained in overlapping relation to each other when secured to said tassel material, said tassel material being separated into groups formed of a predetermined but selectively variable 15 number of strands, said strands being held in spaced relation by said binding material.
6. A machine of the class described including a main frame, a main operating shaft thereon, a pair of other shafts operatively connected to said main driving shaft, a plurality of cams adjustably mounted on each one of said pair of other shafts, a resilient member connected to each of said cams, a plurality of reciprocating elements one operatively connected to and actuated by said cams, adjustable tassel material guiding and holding means arranged on the frame, mechanism adapted to collect and arrange said tassel material into groups of strands, tassel 20 binding material supported on and intermittently drawn through said machine by elements connected to and actuated by said main driving shaft, and adjustable means coacting with and connected to means for drawing 25 said tassel material whereby the binding material is cut into predetermined lengths, bent, and then clampingly engaged with said strand groups to form tassels.
7. A machine of the class described comprising, in combination, mechanism constructed and arranged to engage and intermittently advance tassel material, mechanism adapted to divide and arrange said tassel material into groups, binding mechanism 30 including reciprocating bars adapted to apply binding material to said groups to form tassels, and feeding mechanism for presenting fastening material to said binding mechanism.
- 50 8. A machine of the class described including means for supporting and confining tassel material in a channel, means for retaining, moving and applying binding material intermittently to said tassel material to form groups of tassels arranged in spaced relation and at selectively different spaces apart, and means on the frame for combing said tassels prior to the application of said binding material.
- 55 9. In a machine of the class described comprising a frame provided with a main operating shaft and a pair of other shafts operatively connected to said main driving shaft, a plurality of cams adjustably mounted 60 on each of said pair of other shafts, a pair of die enclosing housings connected to the pair of shafts, a plurality of reciprocating elements within each of the said housings and connected to the adjustable cams, a pair of die blocks adjustably secured in each of said casings, said reciprocating elements being moved transversely of their length by adjustment of said die blocks, substantially as described.
10. A machine of the kind described comprising a frame having a main operating shaft mounted thereon, a pair of coacting other shafts operatively connected to said main shaft, a housing connected to each of said shafts, each of said housings slidably receiving a plurality of reciprocating elements, said reciprocating elements being confined in members adjustably supported in said housing, a plurality of cams adjustably connected to each of said shafts, each of said cams coacting with one of said reciprocating elements, means on the frame for supporting and guiding tassel material and binding material while passing intermittently through the machine, means on said main shaft for periodically combing said tassel material preparatory to the application of said binding material to the tassel material, means to cut said binding material into predetermined sections of variable length, and additional means to apply said cut lengths of binding material clampingly to said tassel material to form groups of tassels arranged in spaced relation.
11. A machine of the class described comprising a frame having a main shaft operatively connected to a pair of other shafts arranged in spaced relation and having a plurality of cams adjustably mounted thereon, a plurality of reciprocating bars held by resilient means in engagement with said cams, one of said pair of other shafts serving to cut, bend and apply wire to binding material intermittently passing through said machine, the other of said shafts coacting with said first mentioned shaft to engage and preliminarily separate strands of said tassel material into groups and to clampingly confine said bent sections of the binding material about said separated strands of tassel material to form groups of tassels arranged in spaced relation.
12. In combination with tassel material supporting and intermittently moving mechanism, means for holding and intermittently applying binding material to said tassel material to form groups of tassels having a bound upper body portion, said body portion having bifurcated depending groups of tassels, each of said groups being entwined by a section of said binding material.
13. A machine of the class described comprising a frame, a pair of housings mounted on said frame, a plurality of reciprocating elements in each of said housings, a spring

connected at one end to each of said reciprocating elements, the other end of said spring being connected to a plate supported on said frame, a corresponding plurality of members actuated by said reciprocating elements for cutting, bending and applying binding material to tassel material movably supported in said frame, means on the frame for intermittently feeding the binding material and the tassel material while said reciprocating elements are actuated, mechanism adapted to arrange said tassel material into groups of strands, means to vary the length of the binding material moved at each successive intermittent movement, and means for preventing the loosening of said binding material from the means for feeding same intermittently through the machine.

14. A machine of the class described comprising a frame, means on said frame for supporting, guiding and intermittently moving tassel material through the machine, other means for moving, guiding and clampingly applying binding material intermittently to said tassel material, said last mentioned means applying said binding material to groups of segregated strands and then applying additional binding material to bifurcated portions of each of said groups of tassels at another point of the said tassels.

15. A machine of the class described comprising a frame having tassel supporting, guiding and moving means coactingly engaged with binding material supporting, guiding, moving and applying means, said applying means being arranged to apply sections of said binding material to said tassel material at an upper and a lower point on groups of strands thereby forming tassels arranged in spaced relation with bifurcated depending portions likewise arranged in spaced relation.

16. In combination, a frame having a main operating shaft and a male and female coacting pair of shafts coupled thereto, a plurality of cutting, moving and clamping elements connected to said male shaft, a plurality of members on said female shaft for receiving and temporarily compressing a plurality of strands of tassel material, means connected to said male and female shafts for altering the relative position of said elements and members whereby tassels are fabricated having an upper bound main body portion, each of said main body portions being divided into a pair of separated depending portions arranged in spaced relation, and means to vary the number of strands and the spaces between said main body portions and said depending pairs of separated portions.

17. A machine of the class described including a frame, a pair of housings mounted on said frame, a plurality of elements adjustably secured within each of said housings, said adjustable elements serving as members

to arrange a plurality of reciprocating bars, a pair of members rockably mounted and intermittently coacting with said reciprocating bars, the bars of each of said housings coacting to cut and clampingly engage sections of binding material with tassel material at different points on said tassel material to provide groups of tassels, having upper body portions arranged in variable spaced relation, and lower bifurcated depending portions likewise arranged in variable spaced positions.

18. A machine of the class described having means for supporting, moving and dividing into groups tassel material, and additional means for supporting, moving and applying binding material to said tassel material at points in proximity to a supporting fringe heading on which said tassel material is secured, said groups of tassels, after the application of said binding material to the upper portion thereof, having open spaces separating the groups of tassels, said binding material being further applied to bifurcated lower sections of said tassel material, one-half of said bifurcated lower portions being clampingly engaged with a bifurcated portion of another of said depending portions, whereby tassels are provided and grouped in upper and lower spaced relation.

19. In a machine of the kind described, means for applying binding material to said tassel material, means to comb said tassel material before binding, and means to form said tassels with a main upper body portion provided with two depending bifurcated sections, said main body portion being clampingly secured by the binding material and each of said depending bifurcated sections being secured to an adjoining bifurcated section of another body portion of another tassel, and elements to apply said binding material at different positions on the upper body portion and on the depending bifurcated sections.

20. In a machine of the class described, means mounted on said machine for guiding and intermittently moving tassel material through the machine, and additional variable means for maintaining in comparatively taut condition said last mentioned means including a removable weight.

21. In a machine of the class described, tassel supporting and intermittently moving means mounted on said frame, coacting elements for intermittently applying binding material to said tassel material while the tassel material is confined in a spring clamping member arranged on a reciprocating element actuated intermittently, said clamping member including a pair of fingers arranged on a U-shaped member having convolutions, said convolutions being operatively engaged by a plurality of pins connected to another portion of the said machine whereby, as said convolutions engage said pins, said fingers

will clampingly confine tassel material while said binding material is applied thereto.

22. A machine of the character described comprising means for feeding fringed material through the machine, means for sequentially grouping the strands of the fringe, means for binding the respective groups of fringe strands in the region of the heading to which said strands are attached, means correlated to said last mentioned means for re-dividing and grouping the first mentioned grouped and bound strands, and means for binding the re-grouped strands to constitute the final tassels and produce an openwork body between said finally created tassels and the original fringe heading.

10 23. A machine of the character described comprising means for feeding fringed material through the machine, means for sequentially dividing the strands of the fringe and gathering the same into separate groups, means for binding the respective gathered groups of said fringe strands to produce tassels, and means for combing said fringe strands preparatory to the grouping and binding operations in creating the tassels.

15 24. A machine of the character described comprising intermittently operating means for feeding a fringed heading through the machine, said means being adjustable for varying the feed of material, cooperating adjustable means for variably dividing the fringe strands and gathering the same into spaced groups, correlated means for binding said spaced groups of strands by independent fastening elements to constitute tassels and feeding mechanism for presenting fastening material to said binding means.

25. A machine of the character described comprising means for progressively passing fringed material through said machine, reciprocatory means opposed on opposite sides of the path of said fringed material and having provision for adjustment to variably divide and gather the respective fringe strands of said material, means for feeding a binding element into cooperative relation with said fringe dividing and gathering means, and means for entwining said binding element about the grouped strands to complete the formation of each individual tassel.

26. A machine of the character described comprising means for supporting and intermittently moving fringed material through the machine, cooperating means for intermittently and sequentially dividing the fringe strands and gathering them into separate spaced groups, and means for binding the respective groups of strands, said last named means having provision for feeding a binding element of the character of wire, severing said binding element into individual sections for each group of fringe strands, and entwining said sections of the binding element about

the respective groups of fringe strands whereby to complete the tassels.

27. In a machine for tasseling fringed heading, cooperating opposed reciprocatory strand grouping devices, cooperating reciprocatory group binding devices, means for passing the fringed heading with its strands between said opposed strand grouping devices whereby to be actuated upon by the latter, and means for supplying a wire-like binding element to said group binding devices.

28. In a machine for tasseling fringed material, means for supporting and passing the material through the machine, means for dividing the fringe strands of said material into predetermined groups and binding said groups in the region of the base heading of the strands, and means for re-dividing and grouping said first grouped and bound strands and binding said re-divided groups whereby to produce finally completed tassels with an openwork body between them and the original fringe heading.

29. In a machine of the character described, means for passing fringed material in an intermittent movement through the machine, said means comprising a reciprocatory element, a cam for moving said element positively in one direction to feed the material, resilient means for actuating said reciprocatory element in the opposite direction, and an adjustable stop for limiting the return movement of said reciprocatory element whereby to vary the feeding movement thereof, means comprising oppositely disposed reciprocatory members for dividing and gathering the fringe strands passed between them into groups, said last named reciprocatory members being cam actuated in the effective working direction thereof and spring returned in the opposite direction, and means for feeding a wire-like binding element into cooperative relation to said strand grouping devices, said means including a device for severing said binding element into separate sections, and means for entwining the said sections of the binding element about the respective groups of fringe strands.

30. In a machine of the character described, means for feeding fringed material intermittently through the machine, said means comprising a friction wheel over which the material is carried, a yieldably cooperating presser roller for holding the material in contact with said friction roller, a ratchet device for rotating said friction wheel, said ratchet device being positively cam driven in the feeding direction and spring restored in the reverse direction, and an adjustable stop for limiting the reverse movement of said ratchet device whereby to vary the feeding length of the fringed material, opposed reciprocatory strand dividing and grouping devices on opposite sides of the path of the

material fed through the machine, said devices being laterally adjustable whereby to variably group and space the fringe strands of the material passed between them, and corresponding reciprocating and adjustable means cooperating with said fringe grouping devices for binding the respective fringe groups to constitute tassels.

31. In a machine of the class described, adjustable means for supporting and intermittently feeding tassel material in a channel, means for dividing the tassel material into separate groups of tassels and spacing the latter apart, means for binding by independent fastening elements the tassels so grouped and spaced, and feeding mechanism for presenting fastening material to said binding means.

32. In a machine of the character described, adjustable means for variably feeding fringed material intermittently through the machine, adjustable means for variably dividing the strands of the fringe into spaced groups, means coacting with said grouping and spacing means for binding the respective groups of the fringe strands, means coacting with said first mentioned grouping and spacing means for dividing and regrouping the said bound groups of fringe strands, and means coacting with said second mentioned strand grouping means for binding the said regrouped fringe strands.

33. In a machine of the character described, adjustable means for variably moving fringed material intermittently through the machine, intermittently operating means for dividing the fringe strands of said material into predetermined spaced groups, and intermittently operating means for entwining a binding material about the respective groups of fringe strands to produce groups of tassels depending from an open-work body thereby created between said tassels and the original heading of the fringed material.

34. In a machine of the character described, means for intermittently and variably feeding fringed material through the machine, intermittently operating means to move transversely of the path of the fringed material in the machine and being adjustable in the direction of travel of said material for dividing the fringe strands into predetermined spaced groups, means coacting with said strand grouping means for binding the respective groups of fringe strands, and similar means for redividing the grouped fringe strands and binding said regrouped strands, said last mentioned means being adjustable with respect to the first mentioned strand grouping means and in the direction of travel of the material.

35. A machine of the class described comprising, in combination, feeding mechanism adapted to feed a strip of fringe material having loose fringe strands, mechanism

adapted to collect and arrange said fringe strands into groups whereby each group of strands is adapted to constitute a tassel, means for applying an independent fastening element to each group, and feeding mechanism for presenting fastening material to said applying means.

36. A machine of the class described comprising, in combination, fringe strand gathering fingers adapted to gather strands of fringe into groups whereby each group is adapted to be fastened to form a tassel, mechanism adapted to feed fringe material to said gathering fingers, mechanism for applying independent fastening elements to each group, and feeding mechanism for presenting fastening material to said applying mechanism.

In testimony whereof, I have signed my name to this specification.

ROBERT E. WALLISER.
